FIG. 1 is a top front perspective view of a photographic flash unit showing my new design;

FIG. 2 is a left-side elevational view thereof;

FIG. 3 is a front elevational view thereof;

FIG. 4 is a rear elevational view thereof; and

FIG. 5 is a bottom plan view thereof.

The essential features of my design are shown in full lines.

I claim:

The ornamental design for a photographic flash unit, substantially as shown and described.
